UNITED STATES PATENT OFFICE.

ERNEST DIDCOTE, OF WOKING, ENGLAND, ASSIGNOR TO ADVERTISING MACHINES
LIMITED, OF LONDON, ENGLAND.

PICTURE-DISPLAYING APPARATUS.

Application filed May 5, 1925. Serial No. 28,076.

This invention relates to improvements in picture display apparatus of the kind wherein groups of curtain rollers are mounted at opposite ends of a supporting frame, and a traveller, moving intermediate the groups, withdraws and replaces individual rollers from the groups at the ends of its path, and unwinds their curtains to display them as it recedes from the groups.

5 In particular, this invention is an improvement in or modification of the invention set forth in my application for letters patent of the United States under Serial Number 757,599, filed Dec. 23, 1924, according to which the apparatus comprises curtain rollers mounted in annular grooves in stationary drums, removable sections in said drums, means operating intermittently serving to bring the rollers in succession into 15 the removable drum sections and means for traversing said drum sections and the rollers therein back and forth across the apparatus.

20 The improvements according to the present invention consist primarily in modifying the construction and arrangement of certain parts of the apparatus so as to permit of the incorporation of a simplified drive for the moving parts, and the provision of means for positively unwinding and winding 25 the curtains so as to eliminate the necessity of employing springs in the curtain rollers as heretofore. These improvements are devised with the main objects of simplifying the construction of the apparatus, and of rendering it more satisfactory and reliable to withstand operation for long and 30 continuous periods.

35 Picture display apparatus embodying the present invention in the preferred form is 40 illustrated in the accompanying drawings, of which:—

Figure 1 is a front elevation partly broken away of the apparatus as a whole;

45 Figure 2 is a side elevation of Figure 1; Figure 3 is a sectional view of a detail taken from line 3—3 of Figure 1;

Figure 4 is a side elevation of a detail of Figure 1;

50 Figure 5 is a plan view of Figure 4; Figure 6 is a sectional elevation on line 6—6 of Figure 4;

Figure 7 is a fragmentary section of Figure 1 taken on line 7—7;

55 Figure 8 is a section on line 8—8 of Figure 7;

Figure 9 is a detail of the drum disc;

Figure 10 is a detail of the curtain roller skate;

Figures 11 and 12 are diagrammatic illustrations of an operation in connection with the traversing mechanism;

Figure 13 is a detail of the traversing mechanism;

Figure 14 is a plan view of Figure 13; and Figures 15, 16, 17 and 18 are details of the curtain winding mechanism.

Referring to the drawings, the frame of the apparatus comprises two parts 1 and 2 secured together by cross bars 3 and distance pieces 4 with straps or caps 5. Cross bars 6 serve to connect the legs of each part of the frame as shown.

So-called drums 7 and 8 are secured to the top members of the frame as by legs 9 and straps 10. Similar drums 11 and 12 are secured to the cross bars 6 at the lower part of the apparatus. Channel members 13 and 14 are secured to the frame by suitable stays in the positions shown as guides for the traversing mechanism to be hereinafter described, and a bar or "back-bone" 15 is secured by straps 16 to the top and bottom of the frame for a similar purpose. Further channel guides 17 are secured by stays 18 at each side of the apparatus also for a purpose hereinafter described.

The curtain rollers 19 are formed in two groups of six each, one above and one below, and are mounted so as to travel in annular grooves in the drums 7 and 8, 11 and 12 respectively. The method of mounting the rollers in the drums is as follows: Referring to Figures 7, 8 and 10, the drum 8 is provided with a flange 20 to form a housing for the bearing 21 in which a driving shaft 22 is journaled. The drum is also provided with annular flanges forming a groove or race 23. A disc 24 is keyed to shaft 22 adjacent the drum, and is slotted at 25 (see Figure 9). The spindle 26 of each curtain roller passes through one slot 25 into the groove or race 23, and is fitted with a shoe or skate 27 upon which are mounted two anti-friction rollers 28. The arrangement is such that, when the disc 24 is rotated, the curtain rollers are moved freely round the groove or race in the drum.

The shaft 22 extends across the top of the apparatus and is keyed to a similar disc 24 serving to move the curtain rollers in the 110

drum 7. The arrangement is similar in regard to the drums 11 and 12. The skates in drums 7 and 12 are keyed to the curtain roller spindles, but those in drums 8 and 11 are rotatably mounted on the spindles. In some cases the skates in the drums 8 and 11 may be dispensed with and the annular grooves in those drums formed to accommodate either the bare spindles or small wheels 10 rotatably mounted thereon.

To the projecting end of shaft 22 is keyed one element 29 of a Geneva movement. The lower shaft 22 for drums 11 and 12 is similarly fitted, and the coacting elements 30 of each Geneva movement are freely mounted on stub shafts 31 journaled in bearings carried by the frame.

The drive for the moving parts is from a motor, indicated at 32, coupled to a worm 20 33 in mesh with a worm wheel 34. This worm wheel is mounted on a shaft 35, carried by the frame in suitable bearings, which shaft is fitted with a sprocket 36. The sprocket 36 transmits the drive from the 25 motor by a chain 37 to a sprocket 38 keyed on the lower shaft 31. On the other end of shaft 31 is keyed a sprocket 39 which is connected by a chain 40 to a sprocket 41 on the upper shaft 31.

30 One end of each curtain 44 on the rollers 19 is secured to a rod or lath 45 (see Figure 3) detachably secured in openings or keyhole slots 46 in the discs 24. When, therefore, a roller is removed from the carrying drums, 35 and drawn up or down by the traversing mechanism hereinafter described, the curtain is exposed.

The traversing mechanism for drawing the curtain rollers up and down, and for 40 changing them, will now be described. On the right-hand side of the apparatus as seen in Figure 1, is a traveler 51 which is adapted to move up and down, and for this purpose carries rollers 53 running in the channel 45 member 14. A slide member 54, formed with a vertical slot 57, and mounted in guides 55 in the traveler, carries a further roller 56 running in the channel 14.

In order to move the traveler, the end of 50 one arm 58 of a bell crank lever (see Figures 4, 5 and 6) is keyed to the chain 40 as by pins 59, this lever being pivoted in ball bearings 60 in the traveler, and having at the end of its other arm 61 a roller 62 engaging in the vertical slot 57. When the chain is in motion, it will be seen that so long as the pins are being carried on a vertical length of chain intermediate the sprockets 39 and 41, the traveler and slide 54 are carried up or down with it as a rigid unit. When, however, the pins commence to ride around one or other of the sprockets, the bell crank must likewise commence to turn on its axis. Such turning being impossible so long 60 as the slide is held fixed by its roller 56

being in the channel 14, horizontal branches 63 are provided in the channel at those points occupied by the roller 56 when the pins enter upon a sprocket (see Figures 11 and 12). The bell crank can therefore turn by reason of the vertical slot 57 within which moves the roller 62 at the end of its arm 61, and since the slide is free to move horizontally. Accordingly, the roller 56 turns into a branch 75 63 of the channel, and the traveler, being thereby prevented from moving vertically, remains stationary in its uppermost (or lowermost) position.

The half-turn of the crank during the time the pins are on the sprocket, causes the slide to reciprocate horizontally and regain its initial position as the pins leave the sprocket. A similar cycle of operations occurs when the pins reach the other sprocket, the horizontal branch there issuing in the opposite direction 80 since the slide moves to the other side. To prevent the rollers 53 carried by the traveler from entering into the branches when they pass the junctions, idle rollers 64 are mounted therein as shown. The traveler carries a block 65 whose upper and lower parts are shaped to fill segmental gaps 66 (see Figure 7) in the drums 8 and 11, and each of these parts is channeled to receive and accommodate a skate 27. These parts of the block 65 95 may be regarded as removable sections of the drums 8 and 11.

When the traveler has moved into its uppermost (or lowermost) position, the annulation of the groove or race in the drum is completed, and, whilst temporarily at rest in this position as hereinbefore described, the shaft 22 and its slotted disc 24 are moved one step forward, so as to transfer the picture roller and skate from the block 65 into the groove or race 23 and introduce a fresh one into the block. This movement of the shaft 22 is effected by the engagement of a pin 59 with an element 67 of the Geneva movement, which rocks the latter together with the element 30 through an angle of 180 degrees as it rides round the sprocket 41, and by means of the pin 68 whereby the element 29 is rocked through an angle of 60 degrees. As will be understood, the operation is repeated at the lowermost position of the traveler, so that there are always two rollers carried in transit across the front of the apparatus, except during the periods of roller changing.

The curtain roller skates are positioned in the block 65 during transit by means of a so-called H-piece or selector lock 70, mounted on the traveler by means of a rod 71 in a sleeve bearing so as to be capable of relative vertical movement. Recesses 73 in the H-piece accommodate and position the spindles 26 of the rollers. The H-piece is secured to a strip or lath 72 which serves the purpose of covering the gap between the two rollers 125 in transit.

The longer arm 74 of a bell crank lever, pivoted at 75 on the traveller, engages by means of a pin 76 and an extended slot 77 with the lath 72. The shorter arm 78 carries a roller 79 running in the channel guide 17 which is deflected at the ends, as shown at 80, so that just before the traveller reaches its uppermost or lowermost position, the lever is rocked and the long arm is depressed 10 or raised respectively. This movement causes relative vertical motion between the H-piece and traveller, so that the former as well as the lath 72 are arrested and kept clear of the drums during the changing of 15 picture rollers.

Apertures 81 are provided in the lath 72, fitted with plain or coloured glass or other suitable material through which light from behind the pictures is projected. These apertures may take the form of stencilled letters or designs.

A second traveller 82 is provided at the other side of the apparatus, which carries rollers 83 mounted in the channel guide 13. 25 The travellers 82 and 51 are connected by cross-bars or tubes 84 which are secured at the middle to a carriage 85 by straps 86. This carriage is provided with rollers 87 bearing against the guide bar 15. The travellers and connecting structure are braced by ties 88 with tension adjustments 89.

Referring to Figures 13 and 14 of the drawings, the traveller is provided with circular openings in which are inserted bush 35 members 90, 91 secured in position by bolts 92 as shown. Within the bush members are housed elements 93 with grooves for holding the curtain roller skates 27, and shafts 94, keyed to these skate holders, extend to the 40 rear of the traveller through ball bearings 95. The rear ends of the shafts 94 are clamped by nuts 96 to winding drums 97, 98, coarse-threaded externally as shown at 99. In engagement with each threaded drum 97 or 98 is a stud or projection 100, carried by a half-ring 101 which is slidably mounted on a rod 102 rigidly secured to the traveller. Recesses 103 are formed in the 45 bush members 90, 91 to permit the curtain roller skates to be inserted and withdrawn.

A cable 104 is wound around the drums 97, 98 and passes over pulleys 105 at the top and bottom of the apparatus. A tension spring 106 is interposed in this cable to 50 compensate for variations in the length of cable off the drums.

The positions of parts shown in Figure 17 are those obtaining when the traveller 51 is stationary at the top of its path, and the groove of the skate holder 93 is then in register with the recesses 103 in the bush member 90 which is itself in register with the annular race in the curtain drum 7. This 55 registration is ensured by the projection 100 abutting against the termination of the

threaded portion of the drum 97. Adjustment for this purpose is readily effected by slackening the nut 96 and disposing the drum and skate holder into the required positions when the traveller 51 is an inch 70 or so short of the top position. That is to say, the drum 97 and the skate holder 93 will be locked against rotation just before the traveller reaches the top of its path.

Similarly, when the traveller 82 is just 75 short of its lowermost position, the drum 98 will be locked against rotation with the groove of its skate holder in register with the lower recesses 103.

It will be seen that rotation of the drums 97, 98 is caused by the winding cable 104 as the traveller 82 moves up and down. When the traveller is moving downwardly, the unrolling of the top picture curtain and the consequent rotation of the curtain roller 80 spindle and its skate controls the rotation of the drum 97, the picture curtain being kept just taut, and the spring 106 in the cable 104 taking up any slack or permitting 85 any slight extension which may occur due to the varying diameter of the curtain on the roller. Whilst the top picture curtain is being unrolled, the bottom picture curtain is positively rolled up by the rotation of the lower drum 98 caused by the cable 104. 90 This curtain is also maintained to the proper degree of tautness since the diameter of the curtain on the roller is increasing, and the paying out of the winding cable from the drum 98 will accommodate itself to the varying 95 speed of rotation of the drum. The spring in the winding cable also permits the slightly premature locking of the respective winding drums, hereinbefore referred to, as the traveller nears the top or bottom of its 100 path.

In order to ensure that the travellers 51 and 82 keep the curtain rollers perfectly horizontal and that their respective skate 110 holders simultaneously register with the races in the drums 7 and 8, the adjustments 89 are provided in the ties 88. By these means it is possible slightly to raise or lower one traveller with respect to the other. The traveller 82 is provided, similarly to the 115 traveller 51, with an H-piece or selector lock for positioning the curtain roller spindles in transit. This selector lock is similarly depressed at the top and bottom of the path of the traveller by means of a bell crank lever having a roller on its short arm in engagement with a channel guide 17.

In order to counterbalance the weight of the traversing mechanism, the latter is connected to a lead weight 108 or weights by 120 means of cables passing around pulleys 107 at the top of the apparatus and attached to or about the top of the carriage 85.

It will be clear from the foregoing description that there are always two rollers 130

in the travellers progressively and alternately winding and unwinding their curtains in order to display and obliterate a continuous succession of pictures.

Without departing from the scope of this invention, it will readily be appreciated by those skilled in the art that many modifications may be made of the construction and arrangement of parts hereinbefore described.

I claim:

1. Picture display apparatus comprising stationary drums having annular grooves therein, curtain rollers mounted in said annular grooves, a removable section in each drum, means operating intermittently to bring the rollers in succession into the said removable sections of said drums, means reciprocating said drum sections and the rollers therein across the apparatus, and means positively rotating the travelling rollers in the same direction of rotation during transit of the rollers one way, and in the opposite direction of rotation during the return transit of the rollers.

2. Picture display apparatus comprising stationary drums, having annular grooves therein, curtain rollers mounted in said annular grooves, a removable section in each drum, means operating intermittently to bring the rollers into the said removable sections of said drums, means reciprocating said drum sections and the rollers therein across the apparatus, including a carriage, and means for positively unwinding and winding the curtains of the rollers in transit comprising winding drums extending laterally from said carriage and a cable engaging said winding drums, whereby positive rotation of the said rollers is assured by the travel of the carriage, the directions of rotation of the rollers being the same in either direction of travel of the carriage, the direction of rotation of the rollers being reversed with the reversal of direction of travel of the carriage.

3. Picture display apparatus comprising a stationary drum having an annular groove therein, a removable section in said drum; a plurality of curtain rollers, spindles terminating said rollers and skates fitted to said spindles, the said skates being mounted in said groove and adapted to travel therein when the removable section is in said drum; means operating intermittently adapted to bring the rollers in succession into the removable section of the drum, means for traversing said removable section and the roller therein into and out of the drum, and means for unwinding and winding the curtains of the said rollers in transit, said means comprising winding drums coupled to the spindles of the rollers, a cable wound around said winding drums, and tension means for maintaining said cable taut.

4. In picture display apparatus, in combination, a group of curtain rollers disposed in spaced relation and rotatable about a common axis, means to retain said curtain rollers in spaced relation, and means to prevent accidental displacement of said curtain rollers from said retaining means; traversing mechanism adapted to successively withdraw curtain rollers from the group and to replace same therein, and winding means adapted positively to unwind and wind the curtains of the rollers, while withdrawn, such winding means including a cable and a drum wound therewith adapted to engage successive curtain rollers during their periods of withdrawal.

5. An apparatus of the character described including groups of curtain rollers disposed in spaced relation, the axes of the rollers of each said group being parallel to and rotatable about a common axis, means to constrain said curtain rollers of each said group in spaced relation, stationary means independent of the aforesaid means to maintain said curtain rollers of each said group in substantially parallel relation with respect to said common axis, means including means traversable intermediate said groups of curtain rollers to disengage said curtain rollers from said constraining means and advance and return said curtain rollers of each said group of curtain rollers and re-engage the same with said curtain roller constraining means, and means for winding and unwinding the curtains of said rollers during the periods of their advance and return, said means comprising pulleys carried by the apparatus, drums coupled to said rollers and a cable wound around said drums and pulleys.

6. An apparatus of the character described including groups of curtain rollers disposed in spaced relation, the curtain rollers of each said group of curtain rollers being parallel with respect to and rotatable about a common axis, a spindle for each said curtain roller, rotatable means engaging said curtain roller spindles to constrain said curtain rollers in spaced relation, means other than said means engaging said curtain roller spindles maintaining said curtain rollers substantially parallel with respect to said common axis to prevent displacement thereof from said constraining means aforesaid, means, including means traversable intermediate said groups of curtain rollers to disengage said curtain rollers from said constraining means and advance and return said curtain rollers of each said group and re-engage the same with said curtain roller constraining means, and means for winding and unwinding the curtains of said rollers during the periods of their advance and return, said means including winding drums coupled to the spindles of the rollers, a cable wound

around said drums and means for keeping said cable taut.

7. An apparatus of the character described and including pairs of stationary drums disposed in spaced relation, annular grooves in said stationary drums, rotatable curtain roller constraining means mounted intermediate the drums constituting the pairs of drums aforesaid, curtain rollers mounted on said 10 constraining means and engaged in said annular grooves in said stationary drums, recesses in said stationary drums, a carriage reciprocable intermediate said pairs of stationary drums, drum sections carried thereby extendable into said recesses, means to intermittently rotate said curtain roller constraining means to bring said curtain rollers into the 15 grooves in said drum sections, means to reciprocate said carriage, and means for continuously rotate said curtain rollers while travelling on said carriage whereby the curtain to be displayed is unwound while the 20 carriage moves in one direction and rewound while the carriage moves in the reverse direction.

25 cable under tension.

8. An apparatus of the character described including pairs of stationary drums disposed in spaced relation, annular grooves in said stationary drums, rotatable curtain roller constraining means mounted intermediate 30 said drums constituting the pairs of drums aforesaid, curtain rollers carried by said constraining means engaged in said annular grooves in said stationary drums, recesses in said stationary drums, a carriage reciprocable intermediate said pairs of stationary drums, drum sections carried thereby extendable into said recesses, means to intermittently rotate said curtain roller constraining 35 means to bring said curtain rollers into the grooves in said drum sections, means to reciprocate said carriage, and means to continuously rotate said curtain rollers while 40 travelling on said carriage whereby the curtain to be displayed is unwound while the carriage moves in one direction and rewound while the carriage moves in the reverse direction. 45

ERNEST DIDCOTE.
